US011357279B2

(12) **United States Patent**
Cotterman

(10) **Patent No.:** US 11,357,279 B2
(45) **Date of Patent:** Jun. 14, 2022

(54) **CLOSURE COMPONENTS FOR A HELMET LAYER AND METHODS FOR INSTALLING SAME**

(71) Applicant: **Boa Technology Inc.**, Denver, CO (US)

(72) Inventor: **Jesse Cotterman**, Evergreen, CO (US)

(73) Assignee: **Boa Technology Inc.**, Denver, CO (US)

(*) Notice: Subject to any disclaimer, the term of this patent is extended or adjusted under 35 U.S.C. 154(b) by 579 days.

(57) **ABSTRACT**

A protective component for a helmet includes a liner or shell that is coupleable with the helmet so that the liner or shell is positioned on an interior surface of the helmet. The liner or shell is made of a low-friction material and is coupled with the helmet so that the liner or shell is moveable relative to the helmet in response to a force being exerted on the helmet. A rear support member is removably coupled with the liner or shell and a tightening mechanism is attached to the rear support member. The tightening mechanism is configured to tension a tension member and thereby tighten the liner or shell, and the helmet, about the wearer's head.

CLOSURE COMPONENTS FOR A HELMET LAYER AND METHODS FOR INSTALLING SAME

CROSS-REFERENCE TO RELATED APPLICATIONS

This application claims priority to Provisional U.S. Patent Application No. 62/503,866 filed May 9, 2017, entitled "Closure Components for a Helmet Layer and Methods for Installing Same," the entire disclosure of which is hereby incorporated by reference, for all purposes, as if fully set forth herein.

BACKGROUND

This invention relates generally to helmets and more specifically to helmet systems that employ reel based tensioning devices. Helmets are worn to protect a wearer's head from trauma due to impacts from surrounding objects. The impact may be due to a fall or may be due to something else, such as an external object striking the helmet. Various restraints are used to secure a helmet to a wearer's head. A common helmet restraint is a strap that is positioned under or around the wearer's chin to secure the helmet atop the head. The strap commonly includes a buckle that allows the strap to be easily unbuckled and removed from about the chin. Reel based tensioning devices may also be employed to secure the strap about the wearer's chin and/or to secure the helmet about the wearer's head.

BRIEF DESCRIPTION

The embodiments herein describe reel based closure devices that may be used with a liner or shell, which is a material protection layer that is disposed within a helmet. The liner or shell helps protect a wearer's head against head injuries by allowing the helmet to move or rotate relative to the head upon impact from an external object. According to one aspect, a protective component for use with a helmet or other headwear includes a liner or shell that is coupleable with the helmet/headwear so that the liner or shell is positioned on an interior surface of the helmet/headwear when coupled with the helmet/headwear. The liner or shell is shaped to correspond to the helmet/headwear and is made of a low-friction material. The liner or shell is also coupled with the helmet/headwear so that the liner or shell is rotatable relative to the helmet/headwear, thereby enabling a relative motion between a wearer's head and the helmet/headwear responsive to a force or an impact being exerted on the helmet/headwear. A rear support member is removably coupleable with a rear portion of the liner or shell and a tightening mechanism is attached to the rear support member. The tightening mechanism is operably coupled with a tension member and includes a rotatable spool and a knob that is configured to rotate the spool. Rotation of the spool in a tightening direction winds the tension member about the spool to tension the tension member and thereby tighten the liner or shell about the wearer's head.

The protective component typically also includes a front support member that is spaced apart from the rear support member forming a gap therebetween. The tension member is coupled to the rear support member and the front support member and extends across the gap between the rear support member and the front support member. Tensioning of the tension member pulls the front support member toward the rear support member. The protective component typically

further includes at least one intermediate tender that is configured to engage the tension member and route the tension member between the front support member and the rear support member.

5 The intermediate tender includes at least one guide within which the tension member is slidably positioned.

The rear support member commonly is a yoke that is configured to engage the back of the wearer's head. The yoke or rear support member also commonly includes an 10 engagement member that is configured to couple with a corresponding engagement member of the liner or shell to couple the rear support member to the rear portion of the liner or shell. The engagement member of the rear support member may include one or more bosses or protrusions and 15 the engagement member of the liner or shell may include one or more apertures. The rear support member may be adjustable relative to the liner or shell so that a position of the rear support member about the wearer's head is adjustable by adjusting the position of the rear support member in 20 relation to the liner or shell. The rear support member may be adjusted relative to the liner or shell by repositioning the boss or protrusion within a different one of said apertures.

The front support member may include a forehead strap that is configured to engage a forehead portion of a wearer's 25 head. The front support member may include one or more temple guides that are positioned near the temples of a wearer's head. The tension member may form a single loop that extends across a right side of the liner or shell and across a left side of the liner or shell to provide a dynamic fit 30 between the right side and the left side.

According to another aspect, a protective component for use with a helmet or other headwear includes a liner or shell that is coupleable with the helmet/headwear so that the liner or shell is positioned on an interior surface of the helmet/ 35 headwear when coupled with the helmet/headwear. The liner or shell is shaped to correspond to the helmet/headwear and is made of a low-friction material. The liner or shell is coupled with the helmet/headwear so that the liner or shell is moveable relative to the helmet/headwear responsive to a 40 force or an impact being exerted on the helmet/headwear. The liner or shell includes a front support member, a rear support member that is spaced apart from the front support member forming a gap therebetween, and at least one intermediate tender that is positioned in the gap between the 45 front support member and the rear support member. A tension member is coupled to the front support member and to the rear support member and extends across the gap between the front support member and the rear support member. A tightening mechanism is configured to adjust a tension of the tension member. The tightening mechanism includes a rotatable spool and a knob that is configured to 50 rotate the spool. Rotation of the spool in a tightening direction winds the tension member about the spool to tension the tension member. The at least one intermediate tender is configured to engage the tension member between the front support member and the rear support member. The at least one intermediate tender includes at least one lace 55 guide within which the tension member slides as the tension of the tension member is adjusted.

60 The at least one intermediate tender may also include an attachment portion that is configured to couple the at least one intermediate tender to the liner or shell. In other embodiments, the at least one intermediate tender is integrally formed with the liner or shell. The at least one intermediate tender is typically configured so that tensioning of the tension member causes the at least one intermediate tender to move inwardly to apply a tightening force to a 65

wearer's head. The at least one intermediate tender may additionally include a first tension member path and a second tension member path that is separated from the first tension member path.

The front support member typically includes a lace guide that is positioned on a distal end of an elongate finger that is configured to wrap circumferentially around the wearer's head. The rear support member may be removably coupleable with the liner or shell. In such embodiments, the rear support member may be a yoke that is configured to engage the back of the wearer's head. The yoke may include an engagement member that is configured to couple with a corresponding engagement member of the liner or shell to couple the yoke to the liner or shell. The engagement member of the yoke may include one or more bosses or protrusions and the engagement member of the liner or shell may include one or more apertures. The yoke may be adjustable relative to the liner or shell so that a position of the yoke about the wearer's head may be adjusted adjusting the position of the yoke relative to the liner or shell. The liner or shell may include a plurality of apertures within which the boss(es) or protrusion(s) of the yoke are positionable and the yoke may be adjusted relative to the liner or shell by repositioning the boss(es) or protrusion(s) within a different one of said plurality of apertures.

BRIEF DESCRIPTION OF THE DRAWINGS

The present invention is described in conjunction with the appended figures:

FIGS. 1A-D illustrate a helmet protective layer that is configured to fit about a wearer's head.

FIGS. 2A-B illustrate an alternative embodiment of a helmet protective layer.

FIGS. 3A-C illustrate an embodiment in which a helmet protective layer includes a pair of straps that a wearer buckles under their chin to secure the helmet protective layer to the wearer's head.

FIGS. 4A-C illustrate another embodiment of a helmet protective layer.

FIGS. 5A-B illustrate a helmet protective layer that employs a strap that is tensioned by a tension member that is operatively coupled with a reel based device.

FIGS. 6A-F illustrate embodiments of coupling a reel based device with the helmet protective layer.

FIGS. 7A-B illustrate other embodiments of attaching a reel based device to the helmet protective layer.

FIG. 8 illustrates an alternative embodiment of coupling a reel based device with a helmet protective layer.

FIG. 9 illustrates an embodiment of coupling a reel based device with a helmet protective layer in a manner similar to that of FIG. 8.

FIGS. 10A-B illustrate a rear support member or yoke that is removably coupleable with a helmet protective layer.

FIGS. 11A-B illustrate an embodiment of coupling a reel based device with a helmet protective layer in a manner similar to that of FIG. 8.

FIGS. 12-13 illustrate embodiments in which a component of a reel based device is direct injection molded onto a helmet protective layer or onto a component that is subsequently attached to the helmet protective layer.

FIGS. 14A-B illustrate a method of coupling a tension component with a helmet protective layer.

FIGS. 15A-B illustrate another embodiment of coupling a guide member with a helmet protective layer.

FIGS. 16A-C illustrate another embodiment of coupling guide members with a helmet protective layer.

In the appended figures, similar components and/or features may have the same numerical reference label. Further, various components of the same type may be distinguished by following the reference label by a letter that distinguishes among the similar components and/or features. If only the first numerical reference label is used in the specification, the description is applicable to any one of the similar components and/or features having the same first numerical reference label irrespective of the letter suffix.

DETAILED DESCRIPTION OF THE DRAWINGS

The ensuing description provides exemplary embodiments only, and is not intended to limit the scope, applicability or configuration of the disclosure. Rather, the ensuing description of the exemplary embodiments will provide those skilled in the art with an enabling description for implementing one or more exemplary embodiments. It being understood that various changes may be made in the function and arrangement of elements without departing from the spirit and scope of the invention as set forth in the appended claims.

The embodiments herein describe reel based closure devices that may be used with a liner or shell, which is a material protection layer that is disposed within a helmet (hereinafter helmet protective layer). The reel based closure devices may be used to tighten and secure the helmet protective layer about a user's head. The helmet protective layer functions by providing a low-friction layer that is integrated into the helmet. The low-friction layer reduces the transfer of a rotational motion or force from the helmet to the user's head in response to an impact of the helmet. Stated differently, the helmet protective layer enables relative motion between the user's head and the helmet regardless of the angle of impact. The relative motion between the user's head and the helmet results in some of the energy of impact being redirected and/or absorbed by the helmet and/or helmet protective layer rather than being imparted to the user's head. This energy redirection and/or energy absorption reduces the force and trauma that the user's head experiences in response to the helmet being impacted.

The helmet protective layer may be a thin, low-friction liner material that is coupled to, or otherwise positioned on, the inside of the helmet between the inner surface of the helmet and the user's head. The helmet protective layer may be coupled with the helmet via various coupling components that are flexible and/or moveable in relation to the helmet. The relative motion of the coupling components enables the energy to be redirected and/or absorbed.

The reel based closure device may be coupled with the helmet protective layer so that the reel based closure device may be operated to tighten and secure the helmet protective layer about the wearer's head. The use of the reel based closure device may enable the helmet protective layer to be worn in a comfortable yet secure manner. The reel based closure device may also enable the wearer to quickly adjust the tension in the helmet protective layer to adjust the fit of the helmet protective layer about the wearer's head for comfort and/or a desired performance.

The reel based closure device (hereinafter reel based device or reel system) is configured to tension a lace or tension member that is guided about the helmet protective layer via one or more guide members, which may be rigid components that are made of plastics or other materials, or which may be flexible and soft components that are made of fabric materials. The reel based device typically includes a knob or dial that may be grasped and rotated by a user. The

knob or dial is commonly coupled with a spool about which the tension member or lace is wound in response to rotation of the knob or dial in a tightening direction. Winding of the tension member or lace about the spool tensions the tension member or lace, which in turn tightens the helmet protective layer about the wearer's head. Exemplary reel based devices are further described in U.S. patent application Ser. No. 14/297,047 filed Jun. 5, 2017, and entitled "Integrated Closure Device Components and Methods", and in U.S. Pat. No. 9,259,056, filed Jun. 21, 2013, and entitled "Reel Based Lacing System", the entire disclosures of which are incorporated by reference herein.

Referring now to FIGS. 1A-D, illustrated is a helmet protective layer 102 that is configured to fit about a wearer's head. A reel based device 104 is coupled with a rear portion of the helmet protective layer 102. The reel based device 104 is coupled with a tension member 106 that is guided about the helmet protective layer 102 via guide member 111. Tensioning of the tension member 106 via the reel based device 104 causes the helmet protective layer 102 to constrict about the wearer's head. The helmet protective layer 102 is configured to allow the helmet protective layer to constrict about the wearer's head. For example, the helmet protective layer may include recessed portions 108 that define or form fingers 109. The fingers 109 may move radially inward against the user's head in response to tensioning of the tension member 106. The guide members 111 may be disposed on the distal ends of the fingers 109 as illustrated in FIG. 1B.

The helmet protective layer 102 also includes a rearward member 110 that is configured to move inward against the back of the user's head as the tension member 106 is tensioned. The reel based device 104 is positioned on the rearward member 110 so that it is accessible to the wearer's hand. For example, the reel based device 104 may extend below the rear surface of the helmet (not shown) so that the reel based device 104 is accessible when the wearer dons the helmet. The rearward member 110 may include a guide member that directs or routes the lace 106 upward toward the fingers.

FIGS. 1C-D illustrate embodiments of guide members that may be employed to guide or direct the lace 106 about the helmet protective layer 102. In one embodiment, the guide member may be a component that is formed or molded onto the helmet protective layer 102, such as the formed guide member 112 illustrated in FIG. 1D. In other embodiments, the guide member may be formed or defined in a distal end of the fingers 109. For example, the distal end of the fingers 109 may be folded backward to form a loop 114 within which the lace 106 is disposed as illustrated in FIG. 1C. The backward folded distal end of the fingers 109 may be coupled together via a heat weld, adhesive bond, RF or sonic weld, and the like.

FIG. 2A illustrates another embodiment of a helmet protective layer 122 that includes a reel based device 128. The helmet protective layer 122 includes a pair of elongate fingers 124 that wrap circumferentially around the wearer's head from the front of the helmet protective layer 122 toward the rear of the helmet protective layer 122. The elongate fingers 124 may be free floating components that are essentially disconnected from the helmet protective layer 122 along a longitudinal length of the fingers 124, or they may be coupled with the helmet protective layer 122 in a manner that allows the fingers 124 to move and flex in relation to the helmet protective layer 122. A distal end of the elongate fingers 124 is attached to lace 126 that is in turn coupled with the reel based device 128. Operation of the reel

based device 128 causes the elongate fingers 124 to compress against the side of the wearer's head and may also cause the rearward portion 130 of the helmet protective layer 122 to move inward against the rear of the wearer's head.

5 The reel based device 128 is coupled with the rearward portion 130 of the helmet protective layer 122 so that the reel based device 128 is accessible to a user.

FIG. 2B illustrates an alternative embodiment of a helmet protective layer 142, which as described above is also 10 referred to as a liner or shell. The helmet protective layer 142 is coupleable with a helmet so that when coupled with the helmet, the helmet protective layer 142 is positioned on an interior surface of the helmet. The helmet protective layer 142 is shaped to correspond to the helmet and is made of a 15 low-friction material. The helmet protective layer 142 is coupled with the helmet so that the helmet protective layer 142 is moveable relative to the helmet responsive to a force or an impact that is exerted on the helmet.

The helmet protective layer 142 includes an intermediate 20 member 148 that is positioned between a front support member or elongate finger 144 (hereinafter elongate finger 144) and a rear support member or rearward portion 150 (hereinafter rearward portion 150). The elongate finger 144 is spaced apart from the rearward portion 150 by a gap and 25 the intermediate member 148 is positioned in the gap. The intermediate member 148 aids in directing or routing a tension member or lace 146 about the helmet protective layer 142 and to and from the reel based device 151. The intermediate member 148 also aids in constricting the helmet protective layer 142 about the wearer's head. As illustrated in FIG. 2B, the elongate finger 144 typically includes 30 a lace guide that is positioned on a distal end of the elongate finger. The lace guide routes or directs the tension member 146 about the distal end of the elongate finger 144. The lace guide may be a temple guide that is configured to be positioned near the temple of a wearer's head.

The tension member 146 is coupled to the elongate finger 144 and to the rearward portion 150 across the gap between the elongate finger 144 and the rearward portion 150. The 40 reel based device 151 is configured to adjust a tension of the tension member 146. The intermediate member 148 is configured to engage the tension member 146 between the elongate finger 144 and the rearward portion 150. The intermediate member 148 includes at least one lace guide 45 within which the tension member 146 slides as the tension of the tension member is adjusted. In some embodiments, the intermediate member 148 includes an attachment portion that is configured to couple the intermediate member 148 to the helmet protective layer 142. In other embodiments, the intermediate member 148 is integrally formed with the helmet protective layer 142 as illustrated in FIG. 2B. The intermediate member 148 is configured so that tensioning the tension member 146 causes the intermediate member 148 to move inwardly and apply a tightening force to a 50 wearer's head. As illustrated in FIG. 2B, in some embodiments, the intermediate member 148 includes a first tension member path and a second tension member path that is separated from the first tension member path. In some embodiments, the tension member may form a single loop 55 that extends across a right side of the helmet protective layer 142 and across a left side of the helmet protective layer 142. The single loop may provide a dynamic fit between the right side and the left side.

In some embodiments, the rear support member or rearward portion 150 is removably coupleable with the helmet protective layer 142. The rearward portion 150 may be a 60 yoke that is configured to engage the back of the wearer's

head. The yoke and its attachment to the helmet protective layer is illustrated in greater detail in FIGS. 10A-B. The description of FIGS. 10A-B is directly relevant to the embodiment illustrated in FIG. 2B and described herein. Thus, it should be realized for purposes of this description, and for the claims, that the illustration and description of FIGS. 10A-B is intended to be combined with the embodiment of FIG. 2B. As such, the entire description of FIGS. 10A-B are equally relevant and applicable to FIG. 2B.

As illustrated in FIGS. 10A-B, the yoke 406 includes an engagement member that is configured to couple with a corresponding engagement member of the helmet protective layer 402 to couple the yoke 406 to the helmet protective layer 402. In the illustrated embodiment, the engagement member of the yoke 406 is at least one boss or protrusion 408 and the engagement member of the helmet protective layer 402 is at least one aperture 410. The yoke 406 is adjustable relative to the helmet protective layer 402 so that a position of the yoke 406 about the wearer's head may be adjusted by adjusting the position of the yoke 406 relative to the helmet protective layer 402. To enable such adjustment, the helmet protective layer 402 may include a plurality of apertures 410 within which the boss or protrusion 408 of the yoke 406 is positionable. In such embodiments, the yoke 406 may be adjusted relative to the helmet protective layer 402 by repositioning the boss or protrusion 408 within a different one of said plurality of apertures 410.

FIGS. 3A-C illustrate an embodiment in which the helmet protective layer 160 includes a pair of straps 164 that a wearer buckles under their chin in order to secure the helmet protective layer 160 to the wearer's head. The helmet protective layer 160 also includes a reel based device 162 that is positioned on the rearward portion of the helmet protective layer 160 and that is operatively coupled with a tension member 166 so that an operation of the reel based device 162 tensions the tension member 166. The tension member 166 is attached to opposing distal ends of the straps 164 so that tensioning of the tension member 166 adjusts the tension in the straps 164 and thereby adjusts the fit of the helmet protective layer 162 about the wearer's head. In some embodiments, the tension member 166 may be simultaneously coupled with the distal end of the straps 164 and with a front portion of the straps so that tensioning of the tension member 166 simultaneously adjust the tension in the distal end and the front portion of the straps.

As described in greater detail in FIGS. 10A-B, the reel based device 172 may be attached to a yoke 170 that is removably coupleable with the helmet protective layer. The yoke 170 may include bosses that snap into engagement with apertures 176 positioned on the helmet protective layer. The apertures 176 may be simply through holes or may include relief cuts to enable the bosses to more easily be attached and/or detached from the helmet protective layer.

FIGS. 4A-C illustrate a helmet protective layer 202 that includes a reel based device 204 and tension member 206 as previously described. The reel based device 204 may be coupled with a rear member 210. The helmet protective layer 202 also includes one or more flexible panels 208a-c that are attached to the helmet protective layer 202. In the illustrated embodiment, the panels 208a-c are configured to pivot or rotate about the helmet protective layer 202. The tension member 206 is guided or directed about the helmet protective layer 202 via the panels 208a-c. Tensioning of the tension member 206 causes one or more of the panels 208a-c to pivot or rotate about the helmet protective layer 202 and/or causes one or more of the panels 208a-c to constrict inward against the surface of the wearer's head. The fit of the

helmet protective layer 202 about the wearer's head may be customized or tailored by employing panels that pivot and/or move radially inward in a desired manner as the tension member 206 is tensioned. The shape of the individual panels 208a-c may be customized based on the desired fit of the helmet protective layer 202. For example, the panels 208a-c may have elongated finger like configurations, may have circular or oval shaped configurations, or any other desired geometry. As illustrated in FIGS. 4B-C, the panels 208a-c may be riveted 211a-b to the helmet protective layer 202 and/or attached using any known attachment method. The use of the panels 208a-c may allow the helmet protective layer 202 to constrict about the wearer's head without buckling or folding the helmet protective layer material.

FIGS. 5A-B illustrate a helmet protective layer 222 that employs a strap 224 that is tensioned by a tension member 226 that is operatively coupled with a reel based device 230. Tensioning of the tension member 226 causes the strap 224 to constrict about the wearer's head and causes the helmet protective layer 222 to also constrict about the wearer's head. In one embodiment the strap 224 is attached to the helmet protective layer 222 via slot pairs that form a loop 228 within which the strap 224 is inserted. The strap 224 may be positioned within the helmet protective layer 222 so that it wraps circumferentially around the wearer's head. The tension member 226 is coupled with the distal end of the straps 224 and is configured to pull the strap 224 rearward as the tension member 226 is tensioned via the reel based device 230. Loops may be formed in the distal ends of the straps 224 through which the tension member 226 is inserted. In other embodiments, a guide member may be attached to the distal end of the straps 224 for guiding or directing the tension member about the helmet protective layer 222. In some embodiments, the straps 224 may directly contact the side of the wearer's head. In such embodiments, a padding or cushion member is typically coupled with the straps 224 to minimize any discomfort in wearing the helmet system.

FIGS. 6A-F illustrate embodiments of coupling a reel based device with the helmet protective layer. In one embodiment, the helmet protective layer 302 includes a flap 306 that is foldable over the reel based device 304. The flap 306 is attached to the helmet protective layer 302 after being folded over the reel based device 304 in order to encase or sandwich the reel based device between the helmet protective layer 302 and the flap 306. In particular, the flap 306 may initially be folded down and extend from the rearward portion of the helmet protective layer 302 as shown by the dashed lines 308 in FIG. 6A. The reel based device 304 may be positioned on the helmet protective layer 302 and the flap 306 may then be folded over the reel based device 304 and attached to the helmet protective layer 302. The flap 306 includes a central hole or aperture through which the knob of the reel based device is positioned after the flap 306 is folded over the reel based device. As illustrated in FIG. 6B, in some instances, the flap 306 could include one or more tabs 310 that are insertable within slots of the helmet protective layer 302 in order to secure the flap 306 in the folded position. As illustrated in FIG. 6C, the flap 306 could include snaps 312 that snap together to secure the flap 306 in the folded position. In yet other instances, the flap 306 could be heat welded, adhesively bonded, or otherwise coupled to the helmet protective layer 302.

As illustrated in FIGS. 6D-E, the helmet protective layer 322 may include an aperture or hole 326 through which the reel based device 324 is inserted and secured. The aperture 326 may be shaped and sized to correspond with the shape

and size of the reel based device 324. The aperture 326 may be slightly smaller in size than a rearward surface of the reel based device 324 so that an interference fit occurs as the reel based device 324 is inserted through the aperture 326 of the helmet protective layer 322. The reel based device 324 may include a channel 328 in which the layer of the helmet protective layer 322 is positioned after the reel based device is inserted through the aperture 326 of the helmet protective layer 322.

As illustrated in FIG. 6F, the reel based device 334 may be directly coupled to the exterior of the helmet protective layer 332. For example, the reel based device 334 may be heat staked 336, riveted, adhesively bonded, RF or sonically welded, and the like to the exterior surface of the helmet protective layer 332.

FIGS. 7A-B illustrate other embodiments of attaching the reel based device to the helmet protective layer. As illustrated in FIG. 7A, the reel based device 344 may be “free floating” about or relative to the helmet protective layer 342. Free floating as used herein means that the reel based device is not fixedly or directly attached to the helmet protective layer 342. Rather, the reel based device 344 is indirectly attached to the helmet protective layer 342. In the illustrated embodiment, the reel based device 344 is indirectly attached to the helmet protective layer 342 via the tension member 346. In particular, the tension member 346 is inserted through holes or apertures 348 that are formed in the helmet protective layer 342. The holes or apertures 348 may be formed in the distal end of a rearward elongate finger(s) of the helmet protective layer 342, or elsewhere as desired. The opposing distal ends of the tension member 346 may be attached to the helmet protective layer 342, or may be coupled together, near a forward portion or elongate fin of the helmet protective layer 342.

The insertion of the tension member 346 through the apertures 348 couples the reel based device 344 with the helmet protective layer 342. Tensioning of the tension member 346 pulls the reel based device 344 into contact with the helmet protective layer 342. Further tensioning of the tension member 346 will cause the helmet protective layer 342 to constrict about the wearer’s head. The tension member 346 may be inserted through apertures of various elongate fingers as illustrated to couple the tension member 346 with the elongated manner so that tensioning of the tension member 346 causes the elongate fingers to constrict about the wearer’s head.

As illustrated in FIG. 7B, the reel based device 354 may be attached to a yoke 356, which is a component that is independent of the helmet protective layer 352 and that is configured to house the reel based device 354 and, in some instances, a portion of the tension member. The use of the yoke 356 may allow the reel based device 354 to extend downward from the helmet protective layer 352 so that it is more easily accessible to the wearer. The use of the yoke 356 may also provide a more rigid base that functions as an anchor point for the reel based device 354. The yoke 356 includes a forked end 358 that is insertable within a slotted aperture 360 of the helmet protective layer 352 to couple the yoke 356 to the helmet protective layer 352. The forked end 358 is one way insertable within the slotted aperture 360 in order to prevent or substantially impede removal of the yoke 356 from the helmet protective layer 352.

FIG. 8 illustrates an alternative embodiment of coupling a reel based device 374 with a helmet protective layer 372. Specifically, the helmet protective layer 372 includes a hole or aperture 375 that defines a plurality of slotted ends 376. In the illustrated embodiment, the aperture 375 defines 3

slotted ends 376. The reel based device 374 includes a base having a tab 378 that extends around a portion of the periphery of the base. In the illustrated embodiment, the tab 378 extends around the entire periphery of the base. The reel based device’s tab 378 and the aperture’s slotted ends 376 are designed so that the tab 378 may be inserted under the slotted ends 376 while remaining sufficiently strong so as to greatly impede removal of the reel based device 374 by pulling the reel based device orthogonally relative to the aperture 375.

FIG. 9 illustrates an embodiment of coupling a reel based device 384 with a helmet protective layer 382 that is similar to the embodiment of FIG. 8. The embodiment of FIG. 9, however, employs a base member 388 that is positioned on an opposite side of the hole or aperture 386 from the reel based device 384. The aperture 386 is shaped and sized so that a bottom surface or portion of the reel based device 384 is insertable through the aperture 386 while a top portion of the reel based device 384 is prevented from being inserted through the aperture 386. The base component 388 is configured to couple or attach to the bottom portion of the reel based device 384 that is inserted through the aperture 386. In this manner the reel based device 384 and the base component 388 may be attached together with the helmet protective layer 382 sandwiched between these two components, which locks or fixedly secures the reel based device 384 to the helmet protective layer 382. In some instances a portion of the base component 388 may be insertable through the aperture 386 to aid in coupling the reel based device 384 to the helmet protective layer 382.

FIGS. 10A-B illustrate a rear support member or yoke 406 that is removably coupleable with the helmet protective layer 402 (i.e., the liner or shell). The reel based device 404 is attached to the yoke 406, which is designed and configured to house the reel based device 404 and/or provide a more rigid anchor point for the reel based device 404. The yoke 406 includes an engagement member that is configured to couple with a corresponding engagement member of the helmet protective layer 402 in order shell to couple the yoke 406 to the rear portion of the helmet protective layer 402. Specifically, an upper portion of the yoke 406 includes one or more bosses 408 (e.g., a pair of bosses) that are insertable within apertures 410 of the helmet protective layer 402. The bosses 408 may be snapped into and out of the apertures 410 of the helmet protective layer 402 in order to attach and/or remove the yoke 406 and reel based device 404 from the helmet protective layer 402. The removability of the yoke 406 and reel based device 404 may allow for an appropriate reel based device 404 to be selected and used based on one or more needs of the helmet protective layer 402.

As illustrated in FIGS. 10A-B, the helmet protective layer 402 may include multiple holes 410 in order to allow for the position of the yoke 406 and reel based device 404 to be adjusted in relation to the helmet protective layer 402. For example, to reposition the yoke 406 in relation to the helmet protective layer 402, the bosses 408 may be removed from the holes 410 and the yoke 406 may be moved upward or downward about the helmet protective layer 402. The yoke 406 may then be attached to the helmet protective layer 402 by reinserting the bosses 408 within the appropriate holes 410. In the illustrated embodiment, the helmet protective layer 402 includes 4 holes 410, which enables the yoke 406 to be moved between 3 positions. In some instances the holes may be connected by a slot 412. The slot 412 enables the bosses 408 to be moved between holes without requiring the bosses to be extracted from the holes. The slot 412 is narrower than the holes and the bosses 408 in order to

11

prevent the bosses 408 from unintentionally migrating between holes. As described herein, the reel based device 404 is operably coupled with a tension member. The reel based device 404 includes a rotatable spool and a knob that is configured to rotate the spool in response to the wearer rotating the knob. Rotation of the spool in a tightening direction winds the tension member about the spool and thereby tensions the tension member and tightens the helmet protective layer 402 about the wearer's head. In some embodiments, the tension member may form a single loop that extends across a right side of the helmet protective layer 402 and across a left side of the helmet protective layer 402, to provide a dynamic fit between the right side and the left side.

FIGS. 11A-B illustrate an embodiment of coupling the reel based device with the helmet protective layer 422 that is similar to the embodiment of FIG. 8. Specifically, a housing or base component 423 of the reel based device (not shown) includes a pair of tabs, 424 and 426, that are insertable within corresponding slots, 430 and 428, of the helmet protective layer 422. In coupling the base component 423 with the helmet protective layer 422, one of the tabs (e.g., 424) is inserted within one of the corresponding slots (e.g., 430) before the other tab (e.g., 426) is inserted within the other corresponding slot (e.g., 428). The tabs, 424 and 426, are positioned underneath the material of the helmet protective layer 422 while the main portion of the base component 423 remains positioned above the material of the helmet protective layer 422. The slots, 428 and 430, are sufficiently strong to greatly impede or prevent unwanted removal of the base component 423 from the helmet protective layer 422.

FIGS. 12 and 13 illustrate embodiments in which a component of a reel based device may be direct injection molded onto the helmet protective layer 442 or onto a component that is subsequently attached to the helmet protective layer 442. Specifically, as illustrated in FIG. 12, a base component or housing 444 of the reel based device may be direct injection molded onto a fabric material or layer 446 that is subsequently attached to the helmet protective layer 442. The fabric material or layer 446 may be a material strip that is positionable on the inner surface of the helmet protective layer 442 and that is attachable thereto via adhesive bonding, mechanical fastening (e.g., hook and loop fasteners), and the like. The direct injection molding of the base component 444 onto the fabric material or layer 446 may provide a secure attachment of the components in a manner that enables easy coupling to the helmet protective layer 442. In some instances, one or more of the guide members 448 for the tension member may be direct injection molded onto the fabric material or layer 446 that is subsequently coupled with the helmet protective layer 442.

In FIG. 13 the base component 454 is direct injection molded onto the helmet protective layer 452 rather than being direct injection molded onto an intermediate layer, such as the fabric material or layer 446 of FIG. 12. The direct injection mold of the base component 454 onto the helmet protective layer 452 itself may eliminate failure points and/or extraneous components that are often present in securing separate components together. The direct injection of the base component 454 onto the helmet protective layer 452 may also provide a fixed anchor point that minimizes or prevents relative motion of the reel based device 454 and the helmet protective layer 452. In some instances, one or more guide members 458 may likewise be direct injection molded onto the helmet protective layer 452 as desired.

12

FIGS. 14A-B illustrate a method of coupling a tension component with the helmet protective layer 502. The tension component is a strap 504 that is operable with the tension member (not shown) to apply a constrictive force to the wearer's head. The strap 504 is positioned in the forefront of the helmet protective layer 502 to apply an inward constrictive force about the forehead of the wearer.

The strap 504 is coupled with the helmet protective layer 502 by inserting opposing ends of the strap 504 through slots 506 that are formed on the helmet protective layer 502. With the opposing ends of the strap 504 inserted through the slots 506, a portion of the strap 504 is positioned on the exterior of the helmet protective layer 502 while another portion of the strap (e.g., the opposing ends of the strap 504) is positioned on the interior of the helmet protective layer 502. In some instances, the opposing ends of the strap 504 may be positioned on the exterior of the helmet protective layer 502 while a more central portion is positioned within the interior of the helmet protective layer 502.

The coupling of the strap 504 with the helmet protective layer 502 maintains the position and orientation of the strap 504 in relation to the helmet protective layer 502. In some embodiments, a central portion of the strap 504 is wider than the slots 506 to prevent the central portion of the strap 504 from being pulled through the slots 506. In another embodiment, the strap 504 includes bosses 520 that are disposed within holes 522 in the helmet protective layer 502. These designs aid in ensuring that the strap 504 maintains a proper alignment about the helmet protective layer 502 and does not shift circumferentially out of alignment relative thereto. In some instances, the helmet protective layer 502 may include relief cuts or portions 512 that enable the helmet protective layer 502 to flex or bend in a desired manner as the helmet protective layer 502 constricts about the wearer's head.

FIGS. 15A-B illustrate another embodiment of coupling a guide member with the helmet protective layer 532. In the illustrated embodiment, the guide member is an intermediate guide 534 that is positioned between the forefront and the rear portion of the helmet protective layer 532. The configuration of the intermediate guides, 534 and 544, may replace the intermediate member illustrated and described in FIG. 2B. Thus, the description of the intermediate guides, 534 and 544, are equally applicable to the embodiment of FIG. 2B.

The intermediate guide 534 is configured to guide or direct a tension member between the forefront and rear portion of the helmet protective layer 532. To couple the intermediate guide 534 with the helmet protective layer 532, a distal end of the intermediate guide 534 is inserted within a slot 540 of the helmet protective layer 532. The distal end of the intermediate guide 534 includes bosses 536, or other coupling features, that are inserted within apertures or holes 538 of the helmet protective layer 532. The insertion of the bosses 536 within the apertures 538 stabilizes the intermediate guide 534 in relation to the helmet protective layer 532.

In another embodiment, the distal end of the intermediate guide 544 may be forked or barbed 546 to allow for a one-way insertion of the distal end of the intermediate guide 544 into the slot 548 of the helmet protective layer. The barbed or forked end 546 may flex inward about a gap 547 as the intermediate guide 544 is inserted through the slot 548 and may flex outward after insertion of the intermediate guide 544 in order to lock or secure the intermediate guide 544 in position.

FIGS. 16A-C illustrate another embodiment of coupling guide members with the helmet protective layer 552. The

guide members in FIGS. 16A-B are ring-shaped guides 554 having a central hole 553 through which the tension member is inserted. An annular channel 555 is formed in the outer surface of the ring-shaped guide 554, which allows the ring-shaped guides 554 to be inserted within an aperture 556 of the helmet protective layer 552. As illustrated, the apertures 556 include a large end that tapers into a more narrow end. The large end is shaped and sized so that the ring-shaped guide 554 may be inserted partially through the aperture 556. With the ring-shaped guide 554 inserted partially through the aperture 556, the ring-shaped guide 554 may be slid into the more narrow end of the aperture 556. The narrow end of the aperture is narrower than the ring-shaped guide 554, but is slightly larger than the annular channel 555 formed in the outer surface of the guide 554, which allows the ring-shaped guide 554 to be positioned in a secure or fixed manner in the narrow end of the aperture 556. The tension member may then be inserted through the central hole 553 of the ring-shaped guide 554. As illustrated, the ring-shaped guides 554 may be used in pairs to route or direct the tension member about the helmet protective layer 552.

FIG. 16C illustrates another guide member 558 that is used to route or direct the tension member. The guide member 558 may be a distal most guide that is positioned on or near a distal end of a path of the tension member. In some instances, the guide member 558 may include a boss 560 having an annular channel that allows the guide member 558 to be inserted within an aperture 556 and fixed or secured in the narrow end of the aperture 556 as described.

Other methods of attaching one or more components of the reel based closure system to the helmet protective layer include the use of magnets, screws, bolts, rivets, or other mechanical fasteners, or involve twisting a portion of a component of the reel based closure system to lock the component in position about the helmet protective layer.

While several embodiments and arrangements of various components are described herein, it should be understood that the various components and/or combination of components described in the various embodiments may be modified, rearranged, changed, adjusted, and the like. For example, the arrangement of components in any of the described embodiments may be adjusted or rearranged and/or the various described components may be employed in any of the embodiments in which they are not currently described or employed. As such, it should be realized that the various embodiments are not limited to the specific arrangement and/or component structures described herein.

In addition, it is to be understood that any workable combination of the features and elements disclosed herein is also considered to be disclosed. Additionally, any time a feature is not discussed with regard in an embodiment in this disclosure, a person of skill in the art is hereby put on notice that some embodiments of the invention may implicitly and specifically exclude such features, thereby providing support for negative claim limitations.

Having described several embodiments, it will be recognized by those of skill in the art that various modifications, alternative constructions, and equivalents may be used without departing from the spirit of the invention. Additionally, a number of well-known processes and elements have not been described in order to avoid unnecessarily obscuring the present invention. Accordingly, the above description should not be taken as limiting the scope of the invention.

Where a range of values is provided, it is understood that each intervening value, to the tenth of the unit of the lower limit unless the context clearly dictates otherwise, between

the upper and lower limits of that range is also specifically disclosed. Each smaller range between any stated value or intervening value in a stated range and any other stated or intervening value in that stated range is encompassed. The upper and lower limits of these smaller ranges may independently be included or excluded in the range, and each range where either, neither or both limits are included in the smaller ranges is also encompassed within the invention, subject to any specifically excluded limit in the stated range. 10 Where the stated range includes one or both of the limits, ranges excluding either or both of those included limits are also included.

As used herein and in the appended claims, the singular forms "a", "an", and "the" include plural referents unless the context clearly dictates otherwise. Thus, for example, reference to "a process" includes a plurality of such processes and reference to "the device" includes reference to one or more devices and equivalents thereof known to those skilled in the art, and so forth.

Also, the words "comprise," "comprising," "include," "including," and "includes" when used in this specification and in the following claims are intended to specify the presence of stated features, integers, components, or steps, but they do not preclude the presence or addition of one or more other features, integers, components, steps, acts, or groups.

What is claimed is:

1. A protective component for use with a helmet or other headwear, the protective component comprising:

a liner or shell that is coupleable with the helmet or other headwear so that the liner or shell is positioned on an interior surface of the helmet or other headwear when coupled with the helmet or other headwear, wherein the liner or shell is shaped to correspond to the helmet or other headwear, the liner or shell is made of a low-friction material, and the liner or shell is coupled with the helmet or other headwear so that the liner or shell is rotatable relative to the helmet or other headwear, thereby enabling a relative motion between a wearer's head and the helmet or other headwear responsive to a force or an impact being exerted on the helmet or other headwear;

a rear support member that is removably coupleable with a rear portion of the liner or shell;

a tightening mechanism that is attached to the rear support member and that is operably coupled with a tension member, the tightening mechanism including a rotatable spool and a knob that is configured to rotate the spool, wherein rotation of the spool in a tightening direction winds the tension member about the spool to tension the tension member and thereby tighten the liner or shell about the wearer's head;

a front support member that is spaced apart from the rear support member forming a gap between the front support member and the rear support member, wherein the tension member is coupled to the rear support member and the front support member and extends across the gap between the rear support member and the front support member, and wherein tensioning of the tension member pulls the front support member toward the rear support member when tensioned;

and at least one intermediate tender configured to engage the tension member and route the tension member between the front support member and the rear support member, the at least one intermediate tender including at least one guide within which the tension member is slidably positioned;

15

wherein the at least one intermediate tender is positioned about the liner or shell so that the at least one guide is positioned on an exterior surface of the liner or shell and so that a first portion of the at least one intermediate tender is positioned on an interior surface of the liner or shell while a second portion of the at least one intermediate tender is positioned on the exterior surface of the liner or shell.

2. The protective component of claim 1, wherein the rear support member comprises a yoke that is configured to engage the back of the wearer's head.

3. The protective component of claim 1, wherein the rear support member comprises an engagement member that is configured to couple with a corresponding engagement member of the liner or shell to couple the rear support member to the rear portion of the liner or shell.

4. The protective component of claim 3, wherein the engagement member of the rear support member comprises at least one boss or protrusion, and wherein the engagement member of the liner or shell comprises at least one aperture.

5. The protective component of claim 1, wherein the rear support member is adjustable relative to the liner or shell such that a position of the rear support member about the wearer's head is adjustable by adjusting the position of the rear support member in relation to the liner or shell.

6. The protective component of claim 5, wherein the liner or shell includes a plurality of apertures within which a boss or protrusion of the rear support member is positionable, and wherein the rear support member is adjustable relative to the liner or shell by repositioning the boss or protrusion within a different one of said plurality of apertures.

7. The protective component of claim 1, wherein the front support member comprises a forehead strap configured to engage a forehead portion of the wearer's head.

8. The protective component of claim 7, wherein the front support member comprises one or more temple guides configured to be positioned near the temples of the wearer's head.

9. The protective component of claim 1, wherein the tension member forms a single loop that extends across a right side of the liner or shell and across a left side of the liner or shell to provide a dynamic fit between the right side and the left side.

10. A protective component for use with a helmet or other headwear, the protective component comprising:

a liner or shell that is coupleable with the helmet or other headwear so that the liner or shell is positioned on an interior surface of the helmet or other headwear when coupled with the helmet or other headwear, wherein the liner or shell is shaped to correspond to the helmet or other headwear, the liner or shell is made of a low-friction material, and the liner or shell is coupled with the helmet or other headwear so that the liner or shell is moveable relative to the helmet or other headwear responsive to a force or an impact being exerted on the helmet or other headwear, wherein the liner or shell comprises:

a front support member;
a rear support member spaced apart from the front support member forming a gap between the front support member and the rear support member; and
at least one intermediate tender positioned in the gap between the front support member and the rear support member;

a tension member coupled to the front support member and to the rear support member, the tension member

16

extending across the gap between the front support member and the rear support member; and a tightening mechanism configured to adjust a tension of the tension member, the tightening mechanism comprising a rotatable spool and a knob configured to rotate the spool, wherein rotation of the spool in a tightening direction winds the tension member about the spool to tension the tension member;

wherein the at least one intermediate tender is configured to engage the tension member between the front support member and the rear support member, wherein the at least one intermediate tender comprises at least one lace guide within which the tension member slides as the tension of the tension member is adjusted, and wherein the at least one intermediate tender is positioned about the liner or shell so that the at least one lace guide is positioned on an exterior surface of the liner or shell and so that a first portion of the at least one intermediate tender is positioned on an interior surface of the liner or shell while a second portion of the at least one intermediate tender is positioned on the exterior surface of the liner or shell.

11. The protective component of claim 10, wherein the at least one intermediate tender comprises an attachment portion that is configured to couple the at least one intermediate tender to the liner or shell.

12. The protective component of claim 10, wherein the at least one intermediate tender is integrally formed with the liner or shell.

13. The protective component of claim 10, wherein the at least one intermediate tender is configured such that tensioning the tension member causes the at least one intermediate tender to move inwardly to apply a tightening force to a wearer's head.

14. The protective component of claim 10, wherein the at least one intermediate tender comprises:
a first tension member path; and
a second tension member path that is separated from the first tension member path.

15. The protective component of claim 10, wherein the front support member comprises a lace guide that is positioned on a distal end of an elongate finger that is configured to wrap circumferentially around the wearer's head.

16. The protective component of claim 10, wherein the rear support member is removably coupleable with the liner or shell.

17. The protective component of claim 16, wherein the rear support member comprises a yoke that is configured to engage the back of the wearer's head.

18. The protective component of claim 17, wherein the yoke comprises an engagement member that is configured to couple with a corresponding engagement member of the liner or shell to couple the yoke to the liner or shell.

19. The protective component of claim 18, wherein the engagement member of the yoke comprises at least one boss or protrusion, and wherein the engagement member of the liner or shell comprises at least one aperture.

20. The protective component of claim 19, wherein the yoke is adjustable relative to the liner or shell such that a position of the yoke about the wearer's head is adjustable by adjusting the position of the yoke relative to the liner or shell.

21. The protective component of claim 20, wherein the liner or shell includes a plurality of apertures within which the boss or protrusion of the yoke is positionable, and

wherein the yoke is adjustable relative to the liner or shell by repositioning the boss or protrusion within a different one of said plurality of apertures.
